(57) **CLAIM**

I claim the ornamental design for the set of covers for a surface mounted gutter, as shown and described.

DESCRIPTION

FIGS. 1-5 are directed to a first embodiment of a set of covers for a surface mounted gutter, showing my new design.

FIG. 1 is an end view thereof,

FIG. 2 is a bottom view thereof,

FIG. 3 is a top plan view thereof,

FIG. 4 is an isometric view thereof,

FIG. 5 is a front view thereof, the rear view being a mirror image,

FIGS. 6-10 illustrate a second embodiment of a set of covers for a surface mounted gutter,

FIG. 6 is an end view thereof,

FIG. 7 is a top plan view thereof,

FIG. 8 is a bottom view thereof,

FIG. 9 is an isometric view thereof,

FIG. 10 is a front view thereof, the rear view being a mirror image,

FIGS. 11-15 illustrate a third embodiment of a set of covers for a surface mounted gutter,

FIG. 11 is an end view thereof,

FIG. 12 is a bottom view thereof,

FIG. 13 is a top plan view thereof,

FIG. 14 is an isometric view thereof,

FIG. 15 is a front view thereof, the rear view being a mirror image,

FIGS. 16-20 illustrate a fourth embodiment of a set of covers for a surface mounted gutter,

FIG. 16 is an end view thereof,

FIG. 17 is a bottom view thereof,

FIG. 18 is a plan view thereof,

FIG. 19 is an isometric view thereof,

FIG. 20 is a front view thereof, the rear view being a mirror image,

(Continued)

FIGS. 21-25 illustrate a fifth embodiment of a set of covers for a surface mounted gutter, FIG. 21 is an end view thereof, FIG. 22 is a bottom view thereof, FIG. 23 is a plan view thereof, FIG. 24 is an isometric view thereof; and, FIG. 25 is a front view thereof, the rear view being a mirror image.

The set of covers for a surface mounted gutter is shown with a symbolic break in its length. The appearance of any portion between the break lines forms no part of the claimed design.
